US00D888075S

(12) **United States Design Patent** (10) Patent No.: **US D888,075 S**
Kuhoff et al. (45) Date of Patent: **** Jun. 23, 2020**

(54) **DISPLAY SCREEN OR PORTION THEREOF WITH A GRAPHICAL USER INTERFACE**

(71) Applicant: **Byton Limited**, Hong Kong (HK)

(72) Inventors: **Carsten Kuhoff**, Sunnyvale, CA (US);
Andre Nitze-Nelson, Pipes Canyon, CA (US)

(73) Assignee: **Byton Limited**, Hong Kong (HK)

(**) Term: **15 Years**

(21) Appl. No.: **29/675,833**

(22) Filed: **Jan. 4, 2019**

(51) LOC (12) Cl. **14-04**

(52) U.S. Cl.

USPC **D14/485**; D14/489

(58) **Field of Classification Search**

USPC D14/485-495

CPC G06F 17/211; G06F 17/212; G06F 3/1251;

G06F 3/0481; G06F 2203/04807

(57) **CLAIM**

The ornamental design for a display screen or portion thereof with a graphical user interface, as shown and described.

DESCRIPTION

The FIGURE is a front view of a display screen or portion thereof with a graphical user interface showing the new design.

The broken lines showing a display screen, portions of the display screen, text, and environmental structure form no part of the claimed design.

1 Claim, 1 Drawing Sheet
